UNITED STATES PATENT OFFICE.

CHARLES C. COX, OF PULASKI, VIRGINIA, ASSIGNOR OF ONE-HALF TO FRANKLIN M. THOMPSON, OF PULASKI, VIRGINIA.

TRAIN-STOPPING APPARATUS.

1,135,881.

Specification of Letters Patent. Patented Apr. 13, 1915.

Application filed May 26, 1914. Serial No. 841,113.

To all whom it may concern:

Be it known that I, CHARLES C. Cox, a citizen of the United States, residing at Pulaski, in the county of Pulaski and State of Virginia, have invented new and useful Improvements in Train-Stopping Apparatus, of which the following is a specification.

This invention relates to improvements in train stopping apparatus and has particular application to automatic mechanism for cutting off the propelling power of a motor car and applying the brakes.

In carrying out the present invention, it is my purpose to provide apparatus of the class described which may be installed on steam and electric railroads and which will be self controlled so that when the propelling power of the motor car has been cut off and the brakes applied, the car carried stopping mechanism will be rendered inactive, as far as the propelling system mechanism and brake system of the motor car is concerned.

It is also my purpose to provide apparatus of the type set forth which will operate efficiently and effectively under all conditions, which will be simple and economical in construction and operation and which will embody comparatively few parts and these so correlated and arranged as to reduce the possibility of derangement to a minimum.

With the above and other objects in view, the invention consists in the construction, combination and arrangement of parts hereinafter set forth in and falling within the scope of the claims.

In the accompanying drawings; Figure 1 is a diagrammatic plan view of a trackway showing the relative positions of the current carrying conductors and track rails. Fig. 2 is a sectional view on the line 2—2 of Fig. 1. Fig. 3 is a diagrammatic view of the car carried mechanism. Fig. 4 is a diagrammatic plan view of the mechanism for operating the controlling element of the propelling power of the motor car, such mechanism being shown on an enlarged scale. Fig. 5 is a horizontal sectional view through such mechanism. Fig. 6 is a vertical sectional view therethrough. Fig. 7 is an enlarged fragmentary plan view. Fig. 8 is a diagrammatic side elevation of the mechanism for operating the engineer's brake valve. Fig. 9 is a horizontal sectional view through

such mechanism, parts being shown in top plan. Fig. 10 is a vertical sectional view therethrough. Fig. 11 is a perspective view of the contact roller or trolley wheel. Fig. 12 is a sectional view through Fig. 11.

Referring now to the drawings in detail, 1 designates a trackway which is preferably divided into blocks of suitable lengths and arranged between the lines of rails of each block is a conductor 2 parallel with the adjacent line of rails and alining axially with the conductors in the adjoining blocks. Each conductor 2 is supported upon posts 3 appropriately fastened to the upper surfaces of the ties of the trackway, and is disposed in a plane above the tread surfaces of the track rails, the conductors 2 being grounded through the posts 3. At switches, grade crossings and similar places the particular conductor 2 is carried under the rails of the switch or intersecting line as illustrated in Fig. 1.

In the embodiment of my invention selected for illustrative purposes, I have shown the car carried mechanism as installed in a steam driven locomotive and in this connection I wish it to be understood that the invention in its useful application, is not limited to steam railroads, but is equally applicable to electric railroads.

4 designates the throttle valve lever movable about the fulcrum post 5 and having the upper end thereof connected with the throttle valve rod 6, while 7 indicates the quadrant plate having the outer edge thereof formed with teeth adapted to be engaged by the latching dog of the throttle lever to hold the latter in the desired position. Mounted upon the fulcrum post 5 of the throttle lever and concentrically thereof is a disk 8 having the periphery thereof formed with teeth 9, while formed integral with the periphery of the disk and projecting radially thereof is an arm 10 lying in face to fact contact with the quadrant plate and capable of movement over such plate. This arm 10 is normally disposed at the forward edge of the quadrant plate, that is, the edge of the plate remote from the boiler and the outer end edge of such arm is beveled as at 11 from the forward end of such edge toward the rear end thereof and projecting outwardly from such edge at the rear end thereof is a lug 12, while connected with the latching dog of the throttle rod and

projecting onto the face of the quadrant plate 7 in the path of movement of the beveled edge 11 and lug 12 on the arm 10 is a lug 13 adapted to be engaged by the beveled edge 11 of the arm 10 in the initial movement of the latter over the adjacent face of the quadrant plate to disengage the dog from the adjacent tooth and, in the continued movement of the arm 10, to be engaged by the lug 12, to swing the throttle valve lever 4 to valve closing position whereby the flow of steam from the steam dome of the boiler to the engine cylinders will be cut off. In the present instance, an electric motor 14 is disposed above the quadrant plate 7 and suitably fastened to the boiler and the armature shaft of such motor is disposed in a vertical plane and has the lower end thereof equipped with a pinion 15 meshing with the teeth 9 on the disk 8 whereby, in the operation of the motor, motion will be transmitted to the disk 8 to swing the arm 10 over the adjacent face of the quadrant plate to unlatch the throttle lever and move the latter to valve closing position. The pinion 15 is splined upon the lower end of the armature shaft of the motor 14 for vertical sliding movement thereon and is provided with an upwardly projecting hub 20 sleeve 16 surrounding the shaft and fixed thereto by means of a set screw or the like is a disk 17, while interposed between the confronting faces of the disk 17 and the pinion 15 is the interconnecting member of a yoke 18. The upwardly projecting limbs of the yoke 18 are disposed within the forked end 19 of a lever 20 fulcrumed upon a post 21 disposed adjacent to the inner edge of the segment. A coiled expansion spring 22 is interposed between the lower side of the lever 20 and a suitable support and acts upon such lever to force the forked end thereof downwardly and so hold the pinion 15 in mesh with the teeth 9 on the disk 8. A portion of the lever 20 between the pivot 21 and the forked end thereof lies adjacent to the upper surface of the quadrant plate 7 and parallel therewith and is disposed in the path of a wedge-shaped block 23 connected with the upper face of the arm 10 at the forward edge thereof, such block having the rear end thereof equipped with an upwardly projecting stop 24. By means of this construction, it will be seen that when the motor 14 is energized and the arm 10 swung over the quadrant plate to unlatch and swing the throttle valve lever, the wedge block 23 will ride under the forked end of the lever 20 thereby swinging the latter about the pivot 21 against the action of the spring 22 to elevate the pinion 15, thus disconnecting the motor from the disk 8 and rendering the arm inactive succeeding the closing of the throttle valve, the stop 24 abutting the adjacent edge of the lever 20 to prevent undue swinging of the arm 10. Connected with the upper end of the armature shaft of the motor 14 is a crank arm 25 and pivotally connected with the outer end of the crank arm is a strip 26 to which is fastened one end of a cord 27, the opposite end of the latter being connected with the controlling valve of the whistle. Thus, when the motor operates to swing the arm 10 to close the throttle valve the crank arm 25 will exert a pull upon the strip 26 and cord 27 thereby opening the whistle valve so that the steam will sound the whistle, the whistle notifying the train crew of the operation of the motor.

28 designates a vertical shaft having the lower end thereof suitably connected with the stem of the engineer's brake valve and fixed to the upper end of such shaft is a disk 29 having a partially circular row of teeth 30 formed on the upper surface at the marginal edge thereof. In the present instance, an electric motor 31 is disposed above the disk 29 and has the armature shaft thereof disposed in a vertical plane. Splined to the lower end of the armature shaft is a pinion 32 meshing with the teeth 30 on the disk 29. The motor 31 is mounted upon an appropriate support and pivoted to such support is one end of a horizontal lever 33 connected through the medium of a pin and slot connection 34 with a collar 35 fixed to the upper face of the pinion 32 and surrounding the armature shaft of the motor 31 concentrically thereof. The free end of the lever 33 terminates above the disk 29 and formed integral with such end of the lever is a disk 36 arranged concentrically with the axis of the disk 29 and formed with a radially extending lug 37 disposed in the path of movement of a wedge block 38 fastened to the upper surface of the disk 29. A spring 39 acts upon the disk end of the lever 33 to hold the disk 36 and the lever 33 in normal position. When the motor 31 is energized, the pinion 32 meshing with the teeth 30 on the disk 29 rotates the latter to revolve the shaft 28 and so actuate the engineer's brake valve to a position to effect an application of the brakes. As the disk 29 rotates, the block 38 rides under the lug 37 and engages the latter with the effect to swing the lever 33 and so slide the pinion 32 out of engagement with the disk 29 thereby disconnecting the motor 31 from the shaft 28. Projecting upwardly from the disk 29 adjacent to the marginal edge thereof are pivot ears 40 and pivoted between the ears 40 is a handle 41 having the inner end thereof disposed below the disk 36 on the lever 33. By means of the handle 41, the parts may be restored to normal position by the engineer.

The motors 14 and 31 are connected in series or parallel with a partial electric cir-

cuit 42 having one terminal grounded upon one of the axles of the locomotive as at 44 and the opposite terminal connected with an arm 45 pivoted at one end as at 46 to the frame of the locomotive. The opposite end of the arm 45 is forked and journaled within the forked end of such arm is a trolley wheel or contact roller 47 riding upon the conductors 2 between the lines of rails on the trackway. A coiled expansion spring 48 has one end bearing upon the upper surface of the arm 45 and the opposite end secured to the adjacent portion of the frame of the locomotive and acts to hold the trolley wheel in frictional engagement with the conductors 2, while surrounding the arm 45 is a substantially U-shaped yoke 49 fastened to an appropriate support and acting to limit the downward movement of the arm 45 under the action of the spring 48 so as to avoid mutilation of the trolley wheel and arm as the car passes over switches, grade crossings and the like. A red lamp 50 indicative of danger is preferably connected in parallel in the partial circuit 42. The conductors 2 are connected with a feeder arranged parallel with the trackway and having one terminal thereof connected to one side of a source of energy, the opposite terminal of such source of energy being grounded.

From the foregoing description taken in connection with the accompanying drawings, the construction and mode of operation of my invention will be readily apparent. The connection between each conductor 2 and the feeder includes a switch which may be under the control of the signal towerman of a signal blade of the adjacent block signal and when the block signal is set at danger the switch is closed, while when the signal is at clear the switch is open. Should a train run into a block against a set danger signal, the trolley wheel 47 engaging the particular conductors 2 and the particular wheel and axle connected with the car carried partial circuit 42 will place the car carried partial circuit in communication with the source of energy thereby forming a complete circuit and energizing the motors 14 and 21 whereby the throttle valve and engineer's brake valve will be actuated as previously described to bring the train to a standstill.

While I have herein shown and described one preferred form of my invention by way of illustration, I wish it to be understood that I do not limit or confine myself to the precise details of construction herein described and delineated, as modification and variation may be made within the scope of the claims without departing from the spirit of the invention.

I claim:

1. In apparatus of the class described, the

combination with the throttle valve lever and quadrant plate of a steam locomotive, of an arm movable over said quadrant plate and adapted to unlock and swing said throttle valve lever to valve closing position, a motor for operating said arm, mechanism holding said motor normally in driving engagement with said arm, and means operable to render said mechanism inactive succeeding the movement of said arm to valve closing position.

2. In apparatus of the class described, the combination with the throttle valve lever and quadrant plate of a steam locomotive, of an arm movable over said quadrant plate and adapted to unlock and swing said throttle valve lever to valve closing position, a motor for operating said arm, mechanism holding said motor normally in driving engagement with said arm, and means operable from said arm to render said mechanism inactive succeeding the movement of said lever to valve closing position.

3. In apparatus of the class described, the combination with the throttle valve lever and quadrant plate of a steam locomotive, of an arm movable over said quadrant plate and having the outer end thereof beveled and formed with a lug, a lug on the latching dog of said lever disposed in the path of movement of the beveled end and lug on said arm, and means for swinging said arm whereby the beveled end thereof will engage the lug on said dog and disengage the latter from the quadrant in the initial movement of the arm and the lug on the arm engage the lug on the dog in the continued movement of the arm to swing the lever to valve closing position.

4. In apparatus of the class described, the combination with the throttle valve lever and quadrant plate of a steam locomotive, of an arm movable over said quadrant plate and having the outer end thereof beveled and formed with a lug, a lug on the latching dog of said lever disposed in the path of movement of the beveled end and lug on said arm, means for swinging said arm whereby the beveled end thereof will engage the lug on said dog and disengage the latter from the quadrant in the initial movement of the arm and the lug on the arm engage the lug on the dog in the continued movement of the arm to swing the lever to valve closing position, and means for disconnecting said arm from the operating means thereof succeeding the closing of the throttle valve.

5. In apparatus of the class described, the combination with the throttle valve lever and quadrant plate of a steam locomotive, of an arm movable over said quadrant plate and having the outer end thereof beveled and formed with a lug, a lug on the latching dog of said lever disposed in the path

4
of movement of the beveled end and lug on said arm, means for swinging said arm whereby the beveled end thereof will engage the lug on said dog and disengage the latter from the quadrant in the initial movement of the arm and the lug on the arm engage the lug on the dog in the continued movement of the arm to swing the lever to valve closing position, and means operable 10 from said arm to disconnect the same from the driving means thereof succeeding the closing of the throttle valve.

6. In train stopping apparatus of the class described, the combination with a controlling element movable about an axis, of a gear wheel secured to said element concentrically of the axis thereof, a second gear wheel meshing with said first gear, a motor 15

connected to said last-mentioned gear wheel, means for energizing said motor to rotate 20 said gear wheels and operate said controlling element, means for sliding said second-named gear wheel longitudinally of its axis to disengage the first-mentioned gear wheel, and means carried by the first-mentioned 25 gear wheel and movable therewith to engage said first means to slide the second-named gear wheel out of engagement with the first-mentioned gear wheel succeeding the operation of said controlling element.

In testimony whereof I affix my signature in presence of two witnesses.

CHARLES C. COX.
